CLAIM

The ornamental design for a thumb-mounted stylus, as shown and described.

DESCRIPTION

FIG. 1 is a perspective view of a thumb-mounted stylus showing my new design in use;

FIG. 2 is a left side view thereof;

FIG. 3 is a right side view thereof;

FIG. 4 is a front view thereof;

FIG. 5 is a back side view thereof;

FIG. 6 is a top view thereof; and,

FIG. 7 is a bottom view thereof.

The broken lines shown in FIG. 1 represent environmental structure and an additional thumb-mounted stylus, and form no part of the claimed design.
